HEEL ATTACHING MACHINES

Lawrence Mawbey, Leicester, England, assignor to United Shoe Machinery Corporation, Boston, Mass., a corporation of New Jersey

Filed Oct. 2, 1958, Ser. No. 764,858

Claims priority, application Great Britain Oct. 12, 1957
11 Claims. (Cl. 1—95)

This invention relates to heel attaching machines and more specifically to machines for attaching wood or plastic heels, for example, to women's shoes by the so-called "push-on" method disclosed in United States Letters Patent No. 2,722,027, granted November 1, 1955 on an application filed in the names of Cyril H. James et al.

There is disclosed in British Letters Patent No. 767,967, which corresponds in general to United States Letters Patent No. 2,768,379, granted October 30, 1956 on an application filed in my name, a machine for attaching wood heels to shoes, said machine in some respects being adapted to operate upon the "push-on" heel attaching method which is disclosed in United States Letters Patent No. 2,391,543, granted December 25, 1945 on an application filed in the names of Joseph W. Carr et al. and relates to the attachment of built-up leather or leather board heels to shoes. Built-up leather heels are commonly attached to the heel ends of outsoles of shoes, such heel ends projecting somewhat beyond the sides of the shoe uppers and forming with said uppers well defined and relatively deep rand creases which are utilized to position the rear ends of the shoes in the machine.

A shoe to which a wood heel of the illustrative Louis type, for example, is to be attached does not have a rand crease such as above defined extending around its rear end and consequently the shoe positioning means disclosed in said Patent No. 2,391,543 is not suited for use in the attachment of Louis heels to shoes. Accordingly, the present machine is provided with shoe positioning and clamping means which is different from the shoe positioning and clamping means disclosed in Patent No. 2,391,543 and by the use of which the operator may readily position in the illustrative machine the heel seat of a shoe which has been fitted for the reception of a wood heel, the present machine also being provided with locking means which acts to prevent disturbance of the shoe on the jack of the machine through successive portions of a split power cycle of the machine.

The illustrative machine herein disclosed comprises a holder or support for a heel, a support or jack for receiving a shoe to which the heel is to be attached, mechanism for inserting double pointed nails part way into the attaching face of the heel and for bending projecting portions of said nails into parallel relation, means for pricking the heel seat of the shoe, gaging means associated with said pricking means for positioning the shoe on the jack and on said pricking means, clamps movable with and with relation to the jack for securing the shoe against movement on the jack, means for operating the pricking means to form in the heel seat of the shoe holes for receiving the nails projecting from the heel, and means for pressing the heel and the heel seat portion of the shoe together to cause the nails to enter pricked holes in the heel seat of the shoe and to be clenched in said heel seat whereby to cause the heel to be attached to the shoe.

The shoe support or jack of the illustrative machine is movable vertically and a shoe mounted on a last is positioned by the operator on said jack with a last pin of the jack engaging a thimble hole of the last and an abutment face of the jack engaged by the upper face of a back cone of the last, said last pin and abutment face being positioned on the shoe support by gaging means mounted on the pricking means. The heel end portion of the shoe is

2

prevented from moving lengthwise laterally of the shoe on the shoe support by a pair of rear heel end shoe engaging members or clamps which engage the rear rounded heel end portion of the counter of the shoe, one at each side of the center of the rear portion and a pair of waist clamping members or clamps which secure the shoe in position on the jack by engagement with its waist portion just forward of the heel breast line, the clamps forming part of heel clamping mechanism. The clamps are yieldingly urged into engagement with the shoe and are locked against movement of separation during the pricking of the shoe and the attachment thereto of a heel, and the jack and the shoe clamping mechanism are locked together against relative movement heightwise and lengthwise of the shoe during and between these operations.

The pricking means of the illustrative machine comprises a block, secured to the upper end of a pricking post, against the upper face of which the heel seat of the shoe is pressed and initially positioned by said gages. The block and the post have slidably mounted in them a plunger which carries at its upper end a plurality of prickers or awls. The block has pivoted on it the above-mentioned gages projecting above the upper face of the block, one of the gages, which is bifurcated, being arranged at the rear of the block and being initially adjustable forwardly and rearwardly of the block and the other two gages lying at opposite sides of the block and being engaged by the feather line portion of the shoe at about the heel breast line of the shoe. The two side gages are urged inwardly toward each other and into engagement with the block by a spring connected to them, said gages being geared together for equal and opposite movement. The upper faces of all three gages are inclined inwardly as they extend toward the block and when a shoe, positioned in the shoe support but not clamped therein, is moved down into engagement with the upper face of the block, the heel end portion of the shoe is positioned forwardly and rearwardly by the rear gage and laterally by the side gages. Indicating means, readily recognizable by the operator, is provided to show whether or not the shoe is properly positioned on the block. The shoe is clamped in the shoe support while it is pricked during the first part of the cycle of the machine and remains so clamped until the heel has been attached to it during the second part of the cycle of the machine.

In the illustrative machine hereinafter described, the heel support and a post of the shoe pricking means are mounted on a carrier which is movable widthwise of the machine between two different operating positions. The shoe support lies to the right of the machine, as viewed from the front, and the nail inserting mechanism lies to the left and when the heel support is beneath the nail inserting mechanism the pricking means is located beneath the shoe support. When the shoe support and the pricking means are in this position the machine is power operated through the first part of its split cycle, initiated by depressing a treadle, causing the nails to be driven part way into the heel in the heel holder or support and projecting portions of the nails to be bent into parallel relation at right angles to the rim of the attaching face of the heel, and also causing the heel seat portion of the shoe on the heel support to be pricked and the heel support to be lowered to withdraw the projecting portions of the nails from the nail inserting mechanism and the shoe to be raised above the upper ends of the shoe positioning gages which are associated with the post of the pricking means so that said post may be movable laterally with the carrier from beneath the shoe. Thereafter the carrier is automatically moved by hydraulic mechanism to the right to carry the heel in its lowered position with the nails driven therein, beneath the heel seat of the shoe. The heel support is then manually

lowered by the operator in response to a second depression of the treadle to cause the holes in the heel seat of the shoe to receive the portions of the nails projecting upwardly from the attaching face of the heel, the treadle being further depressed to initiate the second part of the power cycle causing the shoe to be pressed with substantial force against the heel whereby to attach the heel to the shoe. After the heel has been attached to the shoe the clamps are released from the shoe automatically to release the shoe from the shoe support, and the heel holder or support with the shoe supported thereon is manually moved forwardly by the operator and the shoe is removed from the machine. The operator then actuates a manually operated lever causing the carrier to be moved from its second to its first position ready to attach a heel to the next shoe to be operated upon.

The present invention consists in the novel features hereinafter described, reference being had to the accompanying drawings, which illustrate one embodiment of the same selected for purposes of illustration, said invention being fully disclosed in the following description and claims.

In the accompanying drawings,

FIG. 1 is a front elevation of the illustrative machine; FIGS. 2 and 3 are side elevations of the machine as viewed respectively from the left and from the right;

FIG. 4 is a right side elevation, partly in section, of a shoe support or jack and part of shoe clamping mechanism of the machine;

FIG. 5 is a view, partly in section on the line V—V of FIG. 28, showing details of the jack;

FIG. 6 is a front elevation, partly in section, of shoe pricking mechanism of the illustrative machine;

FIG. 7 is a plan view of the shoe pricking mechanism and of shoe positioning means associated with said mechanism and also of indicating means for visually showing whether a shoe is accurately positioned or not with relation to the pricking mechanism;

FIG. 8 is a right side elevation of the pricking mechanism and of the shoe positioning means associated therewith;

FIG. 9 is a front view of the mechanism shown in FIG. 7;

FIG. 10 is a front elevation of parts which lie at the rear of similar parts shown in FIG. 9;

FIG. 11 is a front elevation, partly in section, of shoe clamping devices of the illustrative machine and means for actuating and locking these devices;

FIG. 12 is a plan view, partly in section, showing devices for clamping a shoe close to the heel breast line thereof and also showing the actuating and locking means therefor;

FIG. 13 is a plan view, partly in section, showing the devices for engaging the heel end portion of a shoe and means for locking these devices;

FIG. 14 is a left side elevation of shoe clamp and lock actuating mechanism of the machine;

FIG. 15 is a front view of part of the mechanism shown in FIG. 14;

FIG. 16 is a left side elevation of portions of the shoe clamp and actuating mechanism partly shown in FIG. 14;

FIG. 17 is a front elevation, partly in section, of a carrier for heel supporting mechanism and shoe pricking mechanism and means for moving the carrier laterally across the machine to two different operating positions;

FIG. 18 is a left side elevation, partly in section, of mechanism for controlling movement of the carrier;

FIGS. 19 and 20 are front and plan views respectively, partly in section, of mechanism for controlling movement of the carrier;

FIG. 21 is a front elevation showing locking mechanism for a valve of the illustrative machine;

FIG. 22 is a plan view, partly in section, of portions of the valve locking mechanism shown in FIG. 21;

FIG. 23 is a right side elevation of the valve locking mechanism;

FIG. 24 is a plan view of some parts of the illustrative machine on the rear of the carrier;

FIG. 25 is a right side elevation of mechanism through which the nail loader is caused to deliver nails to nail inserting and bending mechanism of the machine;

FIG. 26 is a perspective view showing a heel having double ended nails driven into a heel attaching face thereof preparatory to attaching the heel to a shoe;

FIG. 27 shows in perspective the heel end of a shoe which has been pricked for the reception of the heel shown in FIG. 26;

FIG. 28 shows a portion of the shoe supporting jack, which is illustrated in FIG. 4, on an enlarged scale; and

FIG. 29 is a front view of the portion of the jack shown in FIG. 28.

The illustrative machine has a main frame comprising a base 1 and a head 3 bolted to said base. The base 1 has in it a motor 4 which drives a flywheel 7 rotatably mounted on a horizontal drive shaft 5. The flywheel 7 may be operatively connected to the drive shaft 5 by a one-revolution clutch (not shown) controlled by a treadle 9.

The head 3 has slidably mounted in it a vertical plunger 11 on the lower end of which is supported a jack 12 for engaging a last L within a shoe S (FIG. 4) said jack having operatively connected to it shoe engaging and clamping mechanism A. The plunger 11 is reciprocated by the drive shaft 5 by mechanism similar to that disclosed in United States Letters Patent No. 1,195,134, granted August 15, 1916 on an application filed in the name of Joseph Gouldbourn, for actuating the plunger 8 disclosed in this patent whereby to press the shoe S, the heel seat of which has been pricked, against a heel H (FIGS. 26 and 27) which is mounted on a heel support D (FIG. 1) and has had nails D driven into its heel seat. Also operated by the drive shaft 5 is means hereinafter described for pricking the heel seat of the shoe.

Slidably mounted on the front of the head 3 and slightly lower than the jack 12 is the shoe clamping mechanism A. The head 3 has secured to its left side a main bracket 13 corresponding to the bracket referred to as the main bracket 3 in said British Letters Patent No. 767,967 and in said corresponding United States Letters Patent No. 2,768,379. The main bracket 13 carries nail driving and bending mechanism B similar to that disclosed in said Patent No. 2,768,379.

Secured on the head 3, higher than and rearward of the nail driving and bending mechanism B, is a nail loading and assorting mechanism C from which the nails N are supplied to the nail driving and bending mechanism. The nail loading mechanism is similar to that disclosed in United States Letters Patent No. 2,929,066, granted March 22, 1960 on an application filed in the name of Stephen A. Makovski and Robert C. Quarby. The nail driving and bending mechanism C is driven by belts 15 from a pulley 16 secured on the drive shaft 5.

The base 1 has a forwardly projecting portion on which is slidably mounted, for horizontal movement laterally of the machine, a carrier 17. The carrier 17 has mounted on it a heel support D which is similar to that disclosed in British Patent No. 767,967 and also has mounted on it pricking mechanism E for forming holes H' in the fitted heel seat portions of the shoes S to receive the heel attaching nails N which have been driven into the heel attaching faces of said heels as shown in FIG. 26. The pricking mechanism E has associated with it shoe positioning means A1 arranged to position the heel end portion of the shoe S relatively to the pricking mechanism whereby to locate the heel end portion of the shoe in the machine so as to insure that the pricked holes H' in the shoes S shall be in the correct positions to receive

the nails N projecting from the attaching faces of the heels which are to be attached to the shoes.

The forwardly projecting portion of the base 1 has formed in it an oil sump 18 (FIG. 17) in which is located hydraulic mechanism for moving the carrier 17 to and fro transversely of the machine. When the carrier 17 is in its left position, as viewed from the front of the machine, the heel support D is beneath the nail driving and bending mechanism B, and the pricking mechanism E and the shoe positioning means A1 are beneath the jack 12 and beneath the shoe clamping mechanism A. When the carrier 17 is at the right end of its movement the heel support D is beneath the jack 12 and the shoe clamping mechanism A, and the pricking mechanism E and its associated shoe positioning means A1 are in idle positions.

When the heel seat portion of the shoe S has been correctly positioned by the operator on the shoe positioning means A1 associated with the pricking mechanism E it is particularly desirable that the shoe shall not be displaced from that position, since, if the shoe is displaced, it will not be in the correct position to receive the heel H and the nails N therein and accordingly the heel will not be correctly attached to the shoe.

Such displacement may, for example, occur when a member of the jack 12, which engages the top face of the cone, also known as the crown face of the last L, and a last pin secured to and projecting from said member are moved down into close engagement with the thimble of the last and the seat face of the member is pressed against said crown face. If the crown face of the last L is not parallel to the seat face of said member lateral tilting of the last may occur unless the member can tilt freely as it is pressed against the last. Further, the position laterally of the crown face of the last and the last pin hole may vary with relation to the seat face of different lasts and it is desirable that the member and the last pin shall be able freely to move laterally of the machine to accommodate themselves to the position of the crown face and the last pin hole in the thimble of the last.

To enable the member which engages the crown of the last and the last pin projecting downwardly therefrom, readily to move laterally and to tilt as the member is being moved downwardly into engagement with the last and is being pressed against the last under relatively light pressure, the aforesaid spindle 11 (FIGS. 4 and 5) has, on its lower end, and forming part of the jack, means for supporting a post 19 on which is pivoted at 20 a lever or post 21. The upper end of the lever 21 has formed on it teeth 22 which are normally engaged by a toothed plunger 23 slidably mounted on the post 19 and urged downwardly into engagement with the teeth on the lever by a spring 24. The plunger 23 may be raised from the teeth on the lever 21 to allow the lever to be swung forwardly and rearwardly about the pivot 20 by the use of a pin 25 which is secured in the plunger and projects through slots in the post 19 so as to be accessible to the operator. The lower end of the lever 21 has formed on it shelves 27 adapted to support two pairs of rolls 29 which are arranged to move laterally of the machine. The rolls 29 are pivoted on pins 31 which are secured in a sliding member 33. The sliding member 33 has secured in it the outer rings of two ball bearings 35 the inner rings of which are secured on a last engaging member 37 arranged to engage the crown or top face of a last having extending downwardly thereof a last pin 39. The rolls 29 are normally held down against the shelves 27 by a spring 41 seated in a recess of the lever 21 and engaging the plate 43 the ends of which are normally held by the spring against shoulders 45 on plates 47 secured to the lever 21. It will be noted that each of the plates 47 comprises a relatively thick vertical median portion 47a and relatively thin lateral portions

47b. Beneath the plate 43 are two rollers 49. The plate 43 and the rollers 49 lie in a recess 48 in the sliding member 33. The rollers 49 can move along the recess 48 laterally of the machine but the plate 43 is prevented from so moving by the plates 47.

As the shoe is moved down and pressed by the operation of the treadle 9, under relatively light pressure, against the pricking mechanism E, the shelves 27 move down away from the rolls 29 and the spindle 11 presses, through the spring 41, the plate 43, the rollers 49 and the sliding member 33, the last engaging member 37 against the last and the shoe on the last against the pricking mechanism. As soon as the shelves 27 leave the rolls 29 the sliding member 33 is free to move laterally from its initial or idle position on the lever 21 and may be described as floating on the lever 21, the rollers 49 moving laterally between the plate 43, which is pressed against them by the spring 41, and the face at the bottom of the recess 48 in the sliding member 33, and further the last engaging member 37 is free to tilt about the axis of the ball bearings 35. If the aforesaid pin 25 has been raised by the operator the lever 21 may tip lengthwise of the last as the shoe is pressed down whereby to allow the last engaging member to accommodate itself to the crown face of the last if necessary. The member 37 may be described as constituting part of the sliding member 33 since it moves transversely of the machine with the sliding member.

As the plunger 11 is moved further downwardly the lower faces of the shelves 27 come into engagement with faces 51 on the sliding member 33 and the last engaging member 37 is pressed against the last through the ball bearings by the operator and thereafter during the power operation of the machine. The shelves 27 may be described as a presser portion of the lever or post 21 and the faces 51 may be described as a pressure receiving portion of the sliding member 33. The spring 41 may be described as constituting resilient means for normally maintaining the presser portion 27 and the pressure receiving portion 51 of the post or lever 21 and the sliding member 33 respectively spaced from each other.

The shoe pricking mechanism of the illustrative machine (FIG. 6) comprises a lower plunger 53 slidably mounted in the lower portion of the bearing 55 which is secured for adjustment laterally of the machine by means of a screw 54, on the right end portion of the carrier 17. Above the lower plunger 53 is a coaxial upper plunger 57 slidably mounted in the bearing 55 and supporting six prickers 59 which are slidably mounted in a block 61 secured to the upper face of the bearing 55, through which block the prickers are pushed into the heel seat of a shoe pressed downwardly against the upper face of the block 61.

Within the upper and lower plungers 53, 57 is a relatively strong compression spring 63 the lower portion of which is seated in a recess in the lower plunger. The spring 63 may yield if upward movement of the prickers is prevented or unduly resisted. Extending axially through the lower and upper plungers 53, 57 and the spring 63 is a rod 65 rotatably mounted on the plungers 53, 57. The lower end portion of the rod 65 lies in a recess 67 in the lower end portion of the lower plunger 53 and has on it a head 68 arranged to receive an adjusting tool by which it may be rotated. The upper end portion of the rod 65 is reduced in diameter and the reduced portion passes through the upper end portion of the upper plunger 57 and has threaded on it a nut which is normally locked against rotation by a pin but which may be rotated relatively to the upper plunger. A part of the rod, from the shoulder formed by the reduced portion downward, is screw-threaded and on this screw-threaded part is a collar 69 which is prevented from rotating by the engagement of a projection 71 on the collar with a vertical slot 73 in the upper plunger 57. The upper end

of the spring 63 engages the collar 69 and rotation of the rod 65 adjusts the collar 69 thereon and varies the compression of the spring 63. The upper plunger 57 is prevented from rotating in the bearing 55 by the engagement of a screw 75 which is secured to the bearing, with a slot 77 formed in this plunger. The lower plunger 53 is prevented from rotating in the bearing 55 by the engagement of a screw 79 in the bearing with a slot 81 in the plunger. Engagement of the upper end of the slot 81 with the screw 79 limits the downward movement of the lower plunger 53.

The lower end of the lower plunger 53 is, when the pricking mechanism lies beneath a shoe in the shoe support, above a driving plunger 83 of the machine and is moved upwardly and downwardly at appropriate times in each cycle of the machine. When the driving plunger 83 is moved upwardly its upper end engages the lower end of the lower plunger 53 and through the relatively strong spring 63 raises the upper plunger 57 and the prickers 59 to prick a shoe which is being pressed against the block by the heel support. The spring 63 will normally yield a little after the prickers have been moved into engagement, or substantially so, with the metal heel plate (not shown) of the last L but if sufficient resistance to penetration of the shoe S by the prickers 59 is met the spring will yield earlier in the upward movement of the driving plunger 83 and after the spring has thus yielded the upper end of the driving plunger will engage the head 68 on the lower end of the rod 65 and will positively move the rod 65 and the prickers 59 upwardly to cause the prickers to penetrate the work.

The driving plunger 83 is raised by a toggle arrangement similar to that disclosed in said Patent No. 1,195,134 and the lower pivot of the toggle may readily be adjusted upwardly or downwardly to adjust the upper position of the prickers, in accordance with the thickness of the work, to insure that the pricked holes H' penetrate or substantially penetrate the work to the proper depth.

In case the prickers 59 stick in the heel seat of the shoe S means is provided to pull them positively downward away from the shoe on descent of the driving plunger 83. This means comprises a hook member 85 which has a hook 86 and is pivotally connected to the driving plunger 83, said hook 86, when the pricking mechanism has been moved to a position below the jack 12, being adapted to project into a recess 87 formed in the front lower portion of the lower plunger 53. The hook member 85 and the recess 87 in the lower plunger 53 are so arranged that if the prickers stick in the work and thus tend to prevent the upper and lower plungers 53, 57 from moving down with the driving plunger 83 the driving plunger positively pulls them down. The hook 86 on the hook member 85 is normally arranged slightly above the lower end of the recess 87 so that when the carrier 17 is moved to the right to carry the pricking mechanism from beneath the shoe support the recess in the plunger will move freely away from the hook 86 and will return to a position to be engaged by the hook when the pricking mechanism has again moved beneath the jack 12.

The block 61 against which the heel seat of the shoe is pressed has mounted on it shoe positioning devices arranged to position the heel seat of the shoe rearwardly and laterally, that is, with the heightwise median plane of the heel seat portion of the shoe coincident with a vertical median plane 96 of the pricking mechanism or unit E.

The shoe positioning means (FIGS. 7, 8 and 9) comprises a bifurcated back gage 89 at the rear end of the block 61 and centralizing gages 91, one at each side of the block 61 near its forward end. The back gage 89 is pivoted on a horizontal laterally extended pin 93 in the block and is provided with two arms 94 which are arranged equal distances at opposite sides of the vertical

median plane 96 of the block, each arm extending about one-half inch above the upper surface of the block and having a forwardly projecting portion extending over the block toward the middle thereof. Shoe engaging faces 95 of the arms 94 extend downwardly toward the middle of the block and nearly into contact with an upper face thereof at an angle of about 45°. The shoe engaging faces 95 of the arms 94 are adapted to be engaged by the feather line of the heel seat portion of the shoe and to guide the rear rounded heel end position of the shoe as it is moved down onto the block and takes up an appropriate position forwardly and rearwardly as a result of its engagement with these faces. The shoe engaging portions of the back gage 89 are urged rearwardly by a compression spring 97 arranged between the back gage and the block and a screw 99 in the lower end portion of the back gage and engaging the bearing 55 restricts rearward movement of the gage and may be arranged in different positions on said gage to adjust the forward or rearward position of the arms 94 relatively to the block, as may be desired or necessary from time to time.

The centralizing gages 91 at each side of the block 61 are arranged to engage the shoe at about its heel breast line portion and to assist in centralizing this portion on the block and to prevent the shoe from being undesirably swung about its heel end. The centralizing gages 91 are pivoted on parallel spindles 101 rotatably mounted in the lower portion of the block 61. The upper end portions of the centralizing gages 91 are generally similar in shape to the upper end portions of the arms 94 of the back gage and project the same distance at all times above the upper face of the block 61 and have faces 92 extending downwardly and inwardly toward the block and adapted to be engaged by the feather line of the heel seat portion of the shoe. The centralizing gages 91 have horizontal arms 103 provided with teeth 105 which intermesh with one another, said gages being urged toward each other by a tension spring 107 (FIG. 8) which normally holds an adjustable screw 109 in the right centralizing gage in engagement with the block 61. The screw 109 may be adjusted to vary the spacing of the centralizing gages 91 to suit the width of the heel end portion of the shoe to be placed on the block 61.

When a shoe is moved down on the block 61 the shoe engages the faces 95 and 92 respectively of the back and centralizing gages 89, 91 and the gages 91 are moved apart equal distances and assist the operator in locating the shoe centrally of the block, the rear end of the shoe by its engagement with the faces 95 being positioned lengthwise, the shoe thereafter being clamped in the shoe clamping mechanism A as will be hereinafter explained. Close to the centralizing gages 91 is a shoe positioning device which is intended to insure that the shoe shall not be tilted laterally as it is placed on the block 61. This device comprises a vertically yieldable laterally extending plate 158 having an upstanding lug 160 at each end thereof. The lugs 160 are adapted to be engaged by the opposite portions of the heel seat of the shoe near its edge or feather line and close to the heel breast line and are intended to insure that, when the shoe rests on the innermost portions of the lugs, the heel seat of the shoe will be horizontal. As the heel seat of the shoe is moved down into engagement with the upper face of the block 61 the plate 158 moves down with it and tends to assist in keeping the heel seat horizontal without being tilted laterally. As the shoe is pressed downward against the block 61 the centralizing gages 91 yield outwardly equal distances. The plate 158 is normally urged upwardly by a spring 162 in a vertical bore in the plate which engages an inturned flange of a cover plate 164 which is screwed to the block 61 and holds the plate 158 in a guideway in the block. To indicate to the operator whether the shoe is correctly positioned on the block 61 with a heightwise median plane of the heel seat portion

of the shoe lying substantially coincident with the vertical median plane 96 of the block there is provided an indicating arrangement comprising two bell crank levers 111 secured respectively on the spindles 101 the upper end of the right lever as viewed in FIG. 9 being broken away. Each bell crank lever has an upwardly extending arm 111a adjacent to and in front of its associated centralizing gage 91 and has on its upper end portion a downwardly and inwardly inclined face 113 corresponding to the face 92 of the associated centralizing gage 91 and arranged to be engaged by the feather line of the heel seat portion of the shoe as the shoe is placed on the block. The inclined faces 113 serve as centralizing indicators and may be referred to as such. Each bell crank lever 111 has an inwardly extending arm 115 overlying an adjustable screw 116 threaded into the bearing 55, adjustment of the screw serving initially to adjust the faces 113 toward or away from each other in accordance with the type of work to be operated upon. Secured to the rear end of the right spindle 101 is an arm 117 (FIG. 10) and pivoted on the rear end portion of the left spindle 101 is a lever 119, said arm and lever having interengaging teeth 121. The lever 119 has an arm 123 extending to the left as viewed from the front of the machine and this arm has threaded into it a screw 125 which engages the upper end of a plunger 127 slidably mounted in a lug 129 on the carrier 17. Also secured to the left spindle 101 is an arm 131 which engages the upper end of a second plunger 133 parallel to and in front of the plunger 127 and slidably mounted in the lug 129.

The carrier 17 has secured to it a stud 135 on which are pivoted a lever 137 and a lever 139, the lever 137 having an arm 141 an upper face of which is engaged by the plunger 133. A spring 143 in a lug 145 on the carrier engages the underside of the arm 141. The lever 139 has an arm 147 the upper side of which is engaged by the plunger 127 and the lower side of which is engaged by a spring 149 in the lug 145 and lying behind the spring 143. The lever 137 has an upwardly extending arm 151 to which is secured a pointer 153 and the lever 139 has an upwardly extending arm 155 provided with an indicating mark 157.

When the heel seat portion of the shoe is lowered toward the upper end of the block 61 the faces 113 of the bell crank levers 111 are moved apart by engagement with the shoe just forward of the heel breast line. The gauges 91 also move apart and move equal distances irrespective of whether one or both are engaged by the shoe but the bell crank levers 111, which as above stated may be referred to as indicators, can move independently and both engage the shoe whether or not it is presented centrally of the block 61. If the shoe is presented centrally of the block 61 the inclined faces 113 of the bell crank levers 111 are moved equal distances outward and the pointer 153 and the mark 157 are in alinement, thus indicating to the operator that the shoe is correctly positioned on the block. If, however, the shoe is not correctly presented to the block 61, that is if it is not bodily centered or is swung about its rear end a little to one side or the other, the bell crank levers 111 are displaced unequal distances with relation to the vertical median plane 96 and the pointer 153 and the mark 157 will be relatively displaced thus indicating to the operator that the shoe is incorrectly positioned. The shoe may then be moved laterally before or as it is being pressed down onto the block 61 until the pointer 153 and the mark 157 are in alinement thus indicating that the shoe is correctly positioned laterally.

The clamping mechanism A of the illustrative machine comprises front and rear devices for respectively clamping the opposite sides of the shoe just forward of its heel breast line and for engaging opposite sides of the rounded rear end portion of the shoe whereby to prevent it from

moving laterally and lengthwise when it has been correctly positioned on the block 61. The shoe clamping mechanism A is carried by a vertical sliding bracket 159 which corresponds to the sliding bracket referred to as the sliding bracket (27) in United States Letters Patent No. 2,259,568, granted October 21, 1941 on an application filed in the name of Thomas A. Kestell et al., and is adapted to move up or down on the head 3, said bracket 159 being normally supported by a spring plunger 161 (FIG. 4) and, as will hereinafter appear, being movable up and down with the last engaging member 37.

The front shoe clamping devices (FIGS. 4, 11 and 12), which engage the sides of the shoe just ahead of its heel breast line, comprise angled members 163 having opposed faces which are covered with resilient material 165 for engaging the shoe. The members 163, which comprise respectively said resilient material 165, have upper parts arranged to engage the sides of the shoe and lower parts arranged to extend under the inwardly curving sides of the shoe whereby effectively to grip the shoe and to support the same.

Each angled member 163, which may be referred to as a shoe clamp, is pivotally mounted for limited up and down rocking movement to accommodate itself to the shoe on a horizontal forwardly and rearwardly extending pivot 167. Each pivot 167 is carried in a frictionally suspended position by a block 169 which is secured to the front portion of a rearwardly extending arm 171 of a front clamp lever 173. The front end portion of the arm 171 has in it a forwardly and rearwardly extending slot through which passes a bolt 175 used to secure the block 169 to the arm 171, this arrangement providing a forward and rearward adjustment for the angled member 163 to suit the size or style of the shoe.

Each front clamp lever 173 is secured to a vertical spindle 177. The spindles 177 are spaced about two and one-half inches apart laterally of the machine and are rotatably mounted in upper and lower forward extensions 179, 181 (FIG. 4) of the aforesaid sliding bracket 159. Each front clamp lever 173 has a relatively short outwardly extending arm 183 (FIG. 12) having a vertical rounded recess in which is pivotally mounted the front end of a dumbbell-shaped connecting rod 185 the rear ends of which engage recesses in the outer ends of an equalizing bar 187. The equalizing bar 187 is supported between forked arms 189 (FIG. 4) extending rearwardly from the front clamp levers 173.

The central portion of the equalizing bar 187 has pivoted to it by a vertical pin 191 the front end portion of a link 193. The vertical pin 191 extends upwardly into a forwardly and rearwardly extending open-ended slot 195 in the upper extension 179 of the sliding bracket 159 and is guided thereby during its forward and rearward movements. The rear end portion of the link 193 is pivotally connected to the right hand end portion of a front clamp actuating lever 197 which extends to the left and is pivoted about mid-way of its length on a vertical shaft 199 which is rotatably mounted in the sliding bracket 159. The left-hand end of the lever 197 is engaged by one end of a rod 198 the other end of which is connected to mechanism hereinafter described. The clamp actuating lever 197 has an arm 201 extending to the right which is engaged by the ball end of a rod 203 surrounded by a compression spring 205 the front end of which engages a flange 207 on the rod 203 and the rear end of which engages a washer 209 which is engaged by an adjusting screw 211 mounted in a stirrup 213 secured to the sliding bracket 159. The spring 205 acts, when allowed to do so, through the link 193, equalizing bar 187 and the connecting rods 185 to move the front clamping members 163 against a shoe.

After the front clamping devices 163 have engaged the shoe they are locked against outward movement away from the shoe so as to retain the shoe in its correct position. The left-hand spindle 177 to which the left-hand

front clamp lever 173 is secured has secured to it, above the upper extension 179 on the sliding bracket 159, a left lock arm 215 which extends to the right from the left-hand spindle. The right-hand spindle 177 also has secured to it, above the upper extension on the sliding bracket, a right lock arm 217 which extends to the left from the spindle. The inner end portions of the lock arms 215, 217 overlap, the inner portion of the left-hand arm 215 being above the end portion of the right-hand arm 217. The inner end portion of each lock arm 215, 217 has pivotally connected to it the front end portion of a forwardly and rearwardly extending link 219. The rear end portion of each link is pivotally connected to the front end portion of a locking rod 221 which is slidably mounted in the aforesaid sliding bracket 159. The locking rods 221 are parallel and the adjacent sides of their rear portions have flat faces which slightly diverge forwardly and downwardly and are arranged to be engaged by a vertical wedge member 223 (FIG. 11) between the locking rods 221. Upward movement of the wedge member 223 locks the rods 221 against endwise movement by jamming them against fixed faces at their outer sides. The upper end portion of the wedge member 223 has in it a horizontal slot through which passes a pin 225 (FIG. 11) secured in the right-hand end portion of a locking lever 227 (see also FIG. 12). The locking lever 227 extends to the left and is pivoted about mid-way of its length on a horizontal forwardly and rearwardly extending spindle 229 carried by the aforesaid sliding bracket 159. The left-hand portion of the locking lever 227 has on it a cam roll 231 which is pressed down, by a tension spring 233 connected to the locking lever and the sliding bracket, against a cam 235, on the upper face of a cam arm 237 which is secured on the upper end portion of the aforesaid vertical shaft 199 and projects forwardly therefrom. When the cam arm 237 is moved in a clockwise direction, viewed from above, the cam on the cam arm allows the wedge member 223 to be moved upwardly by the spring 233 to lock the locking rods 221 against endwise movement. Thus, both front clamping devices are independently locked against movement. Should however, the clamps 163 tend to move apart, in spite of being locked, the forward diverging faces on the locking rods 221 will bind against the wedge member 223 and prevent such movement of the clamps.

The rear shoe-engaging device comprises a pair of shoe-engaging members 239 (FIG. 13) which may be referred to as shoe clamps and are supported for adjustment toward or from each other on the front ends of a pair levers 241. The levers 241 extend rearwardly and are pivoted on the aforesaid vertical spindles 177. The levers 241 have inwardly extending arms 243 which have on them interengaging gear teeth so that the shoe-engaging members 239 move simultaneously inwardly and outwardly. The right-hand lever 241 has a rearwardly extending arm 245 which is normally held in engagement with a screw 247, mounted in a bracket 249 secured to the sliding bracket 159, by a spring 251 connected to the levers 241. The distance apart of the shoe-engaging members may be varied by adjusting the screw 247. The inwardly extending arm 243 of the left-hand lever 241 has pivoted to it a link 253 pivotally connected to a rod 255 which is slidably mounted in the bracket 249. Slidably mounted in the bracket 249 beneath the rod 255 is a locking rod 257 which is constantly urged to the left by a spring 259, in the bracket 249, towards an adjustable screw 261 to cause the locking rod 257 to bind the rod 255 on the lock. The rod 255 has a lower flat face which is slightly inclined downwardly and rearwardly (FIG. 4) so that any tendency of the shoe-engaging members 239 to move apart, after they have been moved against the shoe and locked by the engagement of the locking rod 257 with the rod 255, causes the inclined face to bind against the locking rod 257. The locking

rod 257 has on its upper side a flat face which is slightly inclined downwardly toward the left and binds against the face on the rod 255 when the spring 259 is allowed to move the locking rod 257 toward the left.

5 The aforesaid screw 261 is mounted in a lever 263 which is secured on the aforesaid shaft 199. The lever 263 has an arm 265 which has projecting from it a lug 267 arranged to engage a face 269 on the bracket 159 to limit movement of the lever 263 in a clockwise direction in FIG. 13. A recess in the arm 265 is engaged by the ball-shaped front end of a rod 271 hereinafter referred to.

15 After a last L in a shoe S has been placed on the last pin 39 the post 19 is moved rearwardly and then downwardly, as hereinafter described, to press the shoe against the aforesaid block 61 of the pricking mechanism E and into the shoe clamping mechanism A. When the shoe has been moved to this position it is desirable that there shall be no relative movement heightwise or forwardly and rearwardly between the shoe-clamping mechanism and the last-engaging member 37 during the interval between the pricking of the shoe and the attaching of the heel to the shoe (during which interval the shoe is raised from the pricking mechanism) as otherwise the pricked holes in the shoe may take up an incorrect position in which they cannot easily receive the nails. For this reason after the shoe has been correctly positioned and gripped between the shoe clamping members, the clamping mechanism is arranged to be locked to the jack. The locking arrangement comprises an arm 273 (FIG. 4) which is secured to a spindle 275 rotatably mounted in a downwardly extending portion 277 of a guide member 279 which is secured to a plate 281 on the lower end of the plunger 11. An arm 283 is secured to 20 the spindle 275 and extends upwardly and has pivotally connected to it the rear end portion of a link 285 the forward end portion of which is pivotally connected to a slide 287, corresponding to the slide referred to as the slide 95 in Patent No. 2,259,568, which carries the post 19. The post 19 is pivotally mounted on a spindle 289 carried by the slide 287. The slide 287 is mounted for forward and rearward movement in a guideway formed partly in the guide member 279 and partly in a similar guide member 289 (FIG. 1) secured to the plate 281. The post 19 has a rearwardly extending arm 291 which has on its rear end a cam roll 293 which engages a cam groove 295 formed in a downwardly extending portion 297 of said similar guide member 289. When the post 19 is drawn forwardly by the operator the roll 293 travels along the cam groove 295 first horizontally and then downwardly, thereby allowing the post to be drawn forwardly and swung upwardly to receive a shoe. The post 19 is held in its forward and upward position by a latch comprising a pin 299 in the post and a spring plunger 301 in the slide 287.

25 The arm 273 extends rearwardly and has pivotally connected to it the upper end portion of a link 305 the lower end portion of which is pivotally connected to the upper end of a lock rod 307 which is slidably mounted in the aforesaid sliding bracket 159. The downwardly extending portion 277 of the guide member 279 has pivotally connected to it the upper end portion of a link 309 the lower end portion of which is pivotally connected to a second lock rod 311 (FIG. 12) slidably mounted in the sliding bracket 159. The lock rods 307, 311 are parallel and relatively close together. Lying between the lock rods 307, 311 is a wedge member 313 (FIG. 12) the rear end portion of which is tapered forwardly and is arranged to engage adjacent side faces of the lock rods 307, 311 when the wedge member is moved forwardly, to lock the rods to the sliding bracket 159. The front end portion of the wedge member 313 is pivotally connected by a pin 314 to the rear end portion of a cylindrical bar 315, which at its forward end carries a cam roll 317, the bar being slidably mounted in

a bracket 316 secured on the forwardly projecting portion 179 of the sliding bracket 159. The cam roll 317 is held against the rear face of a horizontal laterally extending cam bar 319 by a tension spring 321 connected to the pin 314 and to a pin 322 (FIG. 4) extending upwardly from the forwardly projecting portion 179 of the sliding bracket 159. The pin 322 has rotatably mounted on it a supporting roll 323 having a pair of spaced flanges on which the right-hand end portion of the cam bar 319 is supported and against which the front face of the cam bar is pressed by the tension spring 321. The left-hand end portion of the cam bar 319 is pivotally supported in the forked end portion of the aforesaid cam arm 237 which is secured on the upper end portion of the aforesaid vertical shaft 199. A tension spring 326 connected to a pin 328 in the arm 237 and to the sliding bracket 159 tends to move the cam bar 319 toward the left as viewed in FIG. 12. The rear face of the cam bar 319 has a portion which when the vertical shaft 199 is moved in a clockwise direction, viewed from above, and the cam bar 319 is moved to the left by the spring 326 allows the cam roll 317 and wedge member 313 to be moved forwardly by the tension spring 321 and the wedge member to lock the lock rods 307, 311 to the sliding bracket 159. The wedge member 313 therefore locks the sliding bracket 159 to the aforesaid guide member 279 and the slide 287 against forward or rearward movement. When the post 19 of the jack 12 and last-engaging member 37 are raised after the nails N have been driven into the attaching face of the heel and the heel seat of the shoe has been pricked, to allow the heel positioned and clamped upon the heel support D of the carrier 17, as disclosed in British Patent No. 767,967, to be carried beneath the shoe, the sliding bracket 159 and clamping devices rise with them without releasing their hold on the shoe. When during the second power operation or the second part of the split cycle of the machine the shoe is pressed against the heel the spring plunger 161 (FIG. 4) may yield slightly to allow the shoe clamping devices to move down with the shoe.

The rear end portions of the aforesaid rods 198 and 271 are ball-shaped and engage recesses in upwardly extending arms of shoe-clamp and lock actuating levers 327, 329 (FIGS. 14, 15 and 16). Relatively weak springs 330 keep the levers 327, 329 in contact with the rods 271, 198 respectively and the rods in contact with the arm 265 and the front clamp actuating lever 197 respectively. The levers 327, 329 are pivoted, side by side, on a horizontal laterally extending spindle 331 secured in the head 3 of the main frame. A downwardly and rearwardly extending arm 333 of the lock actuating lever 329 has connected to it the upper end portion of a rod 335 the front end of which is connected to mechanism hereinafter described for controlling movement of the carrier 17 laterally of the machine. A downwardly extending arm of each lever 327, 329 is arranged to be engaged by a collar 337 secured on a rod 339 the rear end portion of which is slidably mounted in the head 3 and the front end of which is pivotally connected to an arm 341 secured on a shaft 343 which is rotatably mounted in the head 3, said shaft having secured on its right-hand end portion outside the head 3 a hand lever 345, for a purpose hereinafter described. A tension spring 347 normally causes a lug 349 on the hand lever 345 to be held against a pin 351 in the head 3. Each lever 327, 329 has a forwardly extending arm 353 on the upper front end of which is secured a wear plate 355. The wear plates 355 are arranged to be engaged by a latch plate 357 secured on the rear face of a bar 359 which extends downwardly and at its lower end is pivotally connected to the front end portion of a cam lever 361 (FIG. 16) which is pivoted on a horizontal stud 363 secured in the base 1. The cam lever 361 carries a cam roll 362 which engages a cam groove

in a cam 364 which is secured on a cam shaft 366 which rotates once during each part of the complete machine cycle. The bar 359 is urged toward the wear plates 355 by a spring 360.

5 The bar 359 has pivoted to it near its upper end the rear end portion of a link 365 and the front end portion of the link is pivotally connected to a lever hereinafter described. Just after the machine begins to operate the cam lever 361 (FIG. 16) causes the bar 359 to rise. 10 This rising of the bar 359 allows the spring 205 (FIG. 12) to move the front shoe clamping devices 163 into engagement with the shoe and the springs 233, 321 and 259 (FIGS. 11, 12 and 13) to close the locks. As the bar 359 is moved upwardly it is also swung forwardly 15 to disengage the latch plate 357 from the wear plates 355. To cause the bar 359 to be swung forwardly it is pivotally connected, about mid-way of its length, to the rear end portion of a guiding lever 367 (FIG. 16). The guiding lever 367 is pivoted to the upper end portion 20 of a link 369 the lower end portion of which is pivoted on a bracket 371 secured to the head 3 of the machine frame. The arrangement is such that as the bar 359 rises the link 369 swings forwardly and moves the upper end of the bar forwardly to move the latch plate 25 357 from above the wear plates 355, thereby allowing the clamping devices to clamp the shoe between them. The guiding lever 367 has a forwardly extending arm 373 which as the bar 359 is raised comes into engagement with an adjustable screw 375 in the bracket 371 and limits the forward movement of the bar.

30 The carrier 17 has slidably mounted in each end portion of it a stem 377 (FIG. 17) each of which extends upwardly from a bearing 379, the bearings having rotatably mounted in them shafts 381. Each shaft has secured to each of its end portions a roll 383. The front rolls 383 have formed around them V-shaped grooves 383a which rest on V-shaped guide bars 385 secured on the aforesaid forwardly projecting portion of the base 1. The rear rolls 383 have cylindrical faces which rest on a flat face 386 on the forwardly projecting portion of the base 1. Each stem 377 has in it a recess in which is secured a rod 387 which has around it a spring 389. The spring 389 is confined between a shoulder on the rod and the carrier 17 and normally holds the carrier up against a nut 390 on the rod 387. The nuts 390 are preferably so adjusted that the carrier is normally supported by the rolls 383 a little above the forwardly projecting portion of the base 1. The carrier 17 and mechanisms carried thereby may therefore readily be moved laterally of the machine. When during operation of the illustrative machine pressure is applied to the heel supporting mechanism which is disclosed in British Patent No. 767,967 and to the post of the pricking mechanism the springs 389 yield and the carriage is pressed against the forwardly projecting portion of the base 1 and is supported thereby.

35 The carrier 17 is moved laterally of the machine by hydraulic mechanism which comprises a pair of parallel links 391 (FIGS. 17 and 18) which are pivotally connected at 393 to downwardly extending lugs 394 on the carrier 17. The other end portions of the links 391 are pivotally connected by pins 395 to a pair of arms 397 which are secured on a shaft 399 which is rotatably mounted in a part 401 of a piston bracket 403 which is secured in the forwardly projecting portion of the base 1. The shaft 399 has formed on it gear teeth 405 which mesh with gear teeth 407 on a segment lever 409 which is secured on a shaft 411 rotatably mounted in the piston bracket 403. The segment lever 409 has formed on it gear teeth 413 which mesh with rack teeth 415 formed on a piston rod 417 which is slidably mounted in the piston bracket 403.

40 When the piston rod 417 is raised, as will hereinafter appear, the arms 397 are swung in a counter-clockwise direction as seen in FIG. 17, and move the carrier 17

from its left-hand position to its right-hand position. When the piston rod 417 is lowered from its raised position the carrier 17 is moved to its left-hand position.

The front pin 395 has in it a recess which is arranged to be engaged by one or the other of two spring plungers 422 in the forwardly extending portion of the base 1 when the carrier 17 is at one end or the other of its movement across the machine. The spring plungers 422 prevent downward movement of the links 391 and the arms 397, with consequent movement of the carrier 17 from its end position, should hydraulic pressure, which as will herein-after appear holds the carrier 17 in each of its end positions, be suspended.

The lower end of the piston rod 417 has on it a piston 419 which is slidably mounted in a cylinder 421 formed in the piston bracket 403. The piston 419 is moved up and down in the cylinder 421 by oil supplied by a pump, indicated at 423 (FIG. 17), from a sump 425, formed in the forwardly projecting portion of the base 1, through a valve 426 secured to the rear of the piston bracket 403. The valve 426 comprises a valve bracket 427 and a valve plunger 429 which is slidably mounted in a valve passage 431 in the valve bracket 427. The valve plunger 429 has upper and lower portions 433, 435 which fit slidably in the valve passage 431. The valve plunger 429 has a reduced portion 437 between its upper and lower portions 433, 435 forming a chamber 439. Oil is supplied to the chamber 439 by the pump 423 through a pipe 441 connected to the pump and to the valve bracket 427. The pump takes oil from the sump 425 through a pipe 443.

When the valve plunger 429 is lowered, from the position shown in FIGS. 18 and 19, oil may flow from the chamber 439 along a passage 445, in the valve bracket 427 and in the piston bracket 403, to the underside of the piston 419 to move the piston 419 and piston rod 417 upwardly. When the valve plunger 429 is raised, from the position shown in FIGS. 18 and 19, oil may flow along a passage 447, in the valve bracket 427 and in the piston bracket 403, to the upper side of the piston 419 and will move the piston downwardly if it is in its raised position.

As the piston 419 is raised from its lowest position oil which will be in the cylinder 421 above the piston will pass along the passage 447, above the upper portion 433 of the valve plunger 429 and back to the sump through a pipe 449. When the piston 419 is lowered, oil, which will be below the piston will flow along the passage 445 and through a passage 451 and pipe 449 back to the sump 425.

The valve plunger 429 is moved up and down by a tension spring 453 (FIGS. 18, 19 and 20). One end of the spring 453 is connected to an arm of a control lever 455 which is pivoted on a stud 457 secured in the forwardly projecting portion of the base 1. The other end of the spring 453 is connected to a valve lever 459 which is pivoted on a spindle 461 secured in the forwardly projecting portion of the base 1. The control lever 455 has on it two stop faces 463, 465 one or other of which is arranged to engage a pin 467 secured in the forwardly projecting portion of the base 1 to limit rotation of the control lever 455 in either direction. The control lever 455 has connected to it by a pin and slot connection 469 the aforesaid rod 335 (FIG. 14) through which it may be moved from one position or the other.

The valve lever 459 has secured in it a pin 471 which engages a slot 473 formed in a valve controlling bar 475 which is pivotally connected at 477 to an arm 479 pivoted on a spindle 481 in the piston bracket 403. The arm 479 has connected to it, by a universal coupling, the lower end of a rod 483 the upper end of which is connected, by a universal coupling, to the aforesaid segment lever 409 (FIG. 17).

The valve controlling bar 475 has adjustably secured to it upper and lower blocks 485, 487 which are arranged to engage the pin 471 carried by the valve lever 459.

The blocks 485, 487 are secured by screws in the bar 475 which pass through slots in the blocks and the blocks may be adjusted along the bar 475 toward or from the pin 471 by screws 489 threaded into a projection on the bar 475 and having heads which engage recesses in the blocks 485, 487.

The valve lever 459 has pivotally connected to it the lower end portion of a rod 491 the upper end portion of which is connected to a locking mechanism, hereinafter described, which at desired times during the operation of the machine locks the valve plunger 429 against up or down movement.

The aforesaid rod 491 which is connected to the valve lever 459 is pivotally connected at its upper end to the lower end portion of a rod 493 (FIGS. 21, 22 and 23) which is slidably mounted in a bracket 495 secured on the base 1. Slidably mounted in the bracket 495 is a locking rod 497. The locking rod 497 has on it a face 499 (FIG. 22) which is at an angle to the axis of the locking rod 497, which face, when the locking rod is moved rearwardly, binds against a face on the rod 493 and prevents the rod 493 and valve plunger 429 from moving up or down. The locking rod 497 is moved rearwardly by two springs 501. The locking rod 497 is moved forwardly to release the valve plunger 429 by an arm 503 of a lever 505 which is pivoted on a shaft 507 rotatably mounted in the head 3. The lever 505 has a second arm 509 which has secured in it a pin 511 (FIG. 23). The pin 511 is arranged to engage a lug 513 on a slide 515 which is slidably mounted in the bracket 495. The slide 515 has projecting to the right from it a lug 517 to which is pivoted by a pin 519 a latch or control member 521. A spring 523 connected to the latch 521 and to the head 3 urges the slide 515 forwardly and also tends to swing the latch 521 clockwise as viewed in FIG. 24 about the pin 519.

The lever 505 has an upwardly extending arm 525 which has connected to it one end of a tension spring 527 the other end of which is connected to the head 3, this spring being stronger than the two springs 501 and tending to move the locking rod 497 and slide 515 forwardly. The arm 525 is arranged to be engaged by a pin 529 which is secured in an arm 531 of a lever 533 which is pivoted on the shaft 507. The lever 533 has an upwardly extending arm 535 which is normally held, by the spring 527 against an adjustable screw 537 in the head 3. The left-hand end portion of the shaft 507 has pivoted on it a lever 539 which has an upwardly extending arm 541 to which is pivotally connected the front end portion of the aforesaid rod 365 (FIGS. 14 and 16). The lever 539 has a forwardly extending arm 543 for a purpose herein-after described. The lever 505 has a rearwardly extending arm 545 (FIG. 23) to which is pivotally connected the upper end portion of a rod 547 the lower end of which is so connected to the treadle 9 that when the treadle 9 is depressed to bring a shoe down against the pricking block 61 and to start the machine the rod 547 is raised.

When the illustrative machine is in its stopped position ready to receive a shoe and a heel the locking rod 497 is being held by the arm 503 of the lever 505 in a position which allows the rod 493 to move lengthwise. When the treadle 9 is depressed the lever 505 is moved in a counter-clockwise direction (as seen in FIG. 23) and its arm 503 is moved away from the locking rod 497 and allows the face 499 on the rod to be moved by the springs 501 into engagement with the rod 493 to lock the rod, and therefore the valve plunger 429 against endwise movement, the valve plunger 429 being, at this time, in a neutral position, as shown in FIGS. 18 and 19 and prevents oil from flowing to the cylinder 421. The rod 493 remains thus locked until the treadle is raised at the end of the first part of the cycle of the machine so that no movement of the carrier 17 across the machine can take place until the first part of the cycle has been completed. When the treadle 9 is allowed to rise the lever 505 is turned in a clockwise direction (as viewed in FIG. 23) by the spring 527 and moves

the locking rod 497 forwardly to release the rod 493. The rod 493 is then moved downwardly, as will hereinafter appear, and moves the valve plunger 429 downwardly. Downward movement of the valve plunger 429 allows oil to flow beneath the piston 419 and the carrier 17 to be moved to the right carrying with it a heel, into which nails have been driven and bent, beneath a shoe in the shoe support in which holes have been pricked and the machine then stops.

When the machine stops after the first part of the cycle of the machine, during which nails have been driven into the heel and bent and the shoe has been pricked, it is desirable that the shoe clamping devices shall retain their hold on the shoe so that there shall be no movement of the shoe with relation to the jack in the machine between the insertion of the nails and the attaching of the heel to the shoe.

For this reason means is provided in the illustrative machine, as in the machine disclosed in Patent No. 2,259,568 for retaining the clamping devices against the shoe. This means in the illustrative machine comprises a latch member 551 (FIG. 24) which is pivoted on a vertical pin 553 secured in theforesaid carrier 17 at the rear thereof. The latch member 551 is urged in a counterclockwise direction, as seen in FIG. 24, by a spring 557 and is normally held against a stop face on the carrier.

The lever 539 has, as stated above, a forwardly extending arm 543 above which the latch member 551 is moved when the bar 359 (FIGS. 14 and 16) is moved forwardly as aforesaid. When the bar 359 is moved forwardly the forwardly extending arm 543 is moved down and the latch member 551 which, as the carrier 17 was moved to its left-hand position, came into engagement with the side of the forwardly extending arm 543 and was turned on its pin 553 against the action of the spring 557, as shown in FIG. 24, snaps over the forwardly extending arm and holds the bar 359 in a forward position so that the latch plate 357 on the bar will not engage the wear plates 355 as the bar 359 is moved downwardly near the end of the first part of the machine cycle and the shoe clamping devices will not therefore be moved away from the shoe and the aforesaid locks will not be opened. When the carrier 17 is moved to the right for the attaching of the heel to the shoe the latch member 551 is moved away from the forwardly extending arm 543 so that the bar 359 may move rearwardly and the shoe clamping devices may be moved away from the shoe and the locks opened near the end of the second power operation of the machine, as the bar 359 is moved downwardly.

After the machine stops at the end of the first power operation of the machine the operator may desire to release and remove the shoe if, for example, the nails have not been properly driven into the heel or the desired number of nails have not been driven and it is necessary to recommence the operation. The shoe may be released and the locks opened by forward movement of the aforesaid hand lever 345 (FIG. 14). Forward movement of the hand lever 345 causes the collar 337 to engage the downwardly extending arms of the levers 327, 329 and move the levers in a clockwise direction to release the shoe and open the locks.

When, as aforesaid, the bar 359 is moved upwardly and the levers 327, 329 are moved in a counterclockwise direction the rod 335 moves the control lever 455 (FIG. 18) in a counterclockwise direction until the face 465 engages the pin 467 and the spring 453 lies below the axis of the stud 457 and is in a position to move the valve lever 459 and the valve plunger 429 downwardly. When the operator allows the treadle 9 to rise after the end of the first part of the complete cycle of the machine the spring 527 (FIGS. 21 and 23) moves the lever 505 clockwise which moves the locking rod 497 in a direction to release the rod 493. The valve plunger 429 is thus unlocked and is immediately moved downwardly by

the spring 453 until a shoulder 561 (FIG. 18) on the valve plunger engages a plate 563 secured on the valve bracket 427. When the valve plunger 429 is in this position the lower portion 435 of the valve plunger has just fully uncovered the passage 445 and oil, under the full pressure supplied by the pump, may flow beneath the piston 419 to raise the piston and to move the carrier toward the right.

As the piston 419 rises the arm 479 and valve controlling bar 475 are raised by the connection of the arm 479, through the rod 483, to the segment lever 409. As the valve controlling bar 475 rises the slot 473 therein moves upwardly past the pin 471 in the valve lever 459, until the bottom of the slot, or the block 487, engages the pin 471. During this part of the upward movement of the piston 419 which is about half its total upward movement, the piston has been under the full pressure of the oil and the carrier 17 has been moving to the right at relatively high speed. As the piston 419 continues to rise the valve lever 459 also rises and raises the valve plunger 429. The passage 445 is therefore gradually closed by the lower portion 435 of the valve plunger 429 and the speed of the carrier 17 is gradually reduced until, when the carrier 17 has arrived in its right-hand position, the passage 445 is fully closed. The block 487 may, however, be so adjusted that the passage 445 is not quite closed when the common carrier reaches its right-hand position and therefore some pressure will continue to be exerted below the piston which holds the carrier in its right-hand position.

As the bar 359 (FIGS. 15 and 16) is moved downwardly during the second part of the machine cycle the rod 335 moves the control lever 455 in a clockwise direction in FIG. 18 so that the spring 453 is in a position to move the valve plunger 429 upwardly.

When the carrier 17 is in its right-hand position the aforesaid latch 521 (FIG. 22) is being prevented from moving forwardly by a plate 563 (FIG. 24) fixed on the carrier which then lies in front of the front end of the latch 521. The locking rod 497 is thus prevented from being moved forwardly to release the rod 493 and valve plunger 429. The carrier 17 cannot therefore be returned to its left-hand position until the front end of the latch 521 has been moved laterally from behind the plate 563 so that the locking rod 497 may be moved forwardly by the spring 527 to release the rod 493 and valve plunger 429 to the action of the spring 453 which then moves the valve plunger 429 upwardly.

To swing the latch 521 its rear end portion is engaged by a pin 565 secured in the right-hand end portion of a bar 567. The bar 567 extends in a direction across the machine and its left-hand end portion is pivotally connected to the upper end portion of an arm 268 (FIG. 2) which is secured on the rear end of a horizontal forwardly extending shaft 569 rotatably mounted in the forwardly projecting portion of the base 1. The front end of the shaft 569 has secured to it a hand lever 571 by which the bar 567 may be moved to the left to swing the front end of the latch 521 away from plate 563 and allow the latch to be moved forwardly. The bar 567 is moved to the right by a spring, its movement in this direction being limited by a slot 572 in the bar and a screw in the head 3.

When a heel H has been attached to a shoe S and the machine has come to rest the operator moves the heel support D with the heel and its attached shoe supported thereby forwardly to release the heel from the heel support and the shoe is removed. If the operator should actuate the hand lever 571 before the heel support has been moved forwardly and therefore before the heel has been released, the shoe, as the carrier 17 moves to the left, would come into engagement with the nail inserting mechanism and would probably be damaged thereby. In order to prevent this happening means is provided in the illustrative machine for preventing operation of the

hand lever 571 until the heel support has been moved forwardly. This means comprises a recess in the rear edge of the bar 567 which, when the heel support is in its rearward position, is engaged by an edge portion of a vertical bar 573 (FIG. 23). The upper end portion of the bar 573 has in it a slot 575 which is engaged by a pin 577. The pin 577 is secured in one arm of a bell crank lever 579 which is pivoted on a stud 581 secured in a bracket 582 fixed on the head 3. The lower end portion of the bar 573 is guided by a slot 583 in the bar and a pin 585 in the head 3. A downwardly extending arm 587 of the bell crank lever 579 has on it an angled face 589 arranged to be engaged by a horizontal forwardly and rearwardly extending rod 591 (FIG. 2) slidably mounted in the heel support and is moved rearwardly as a heel is clamped in the heel support. When the carrier 17 is moved from its left-hand position to its right-hand position the rod 591 (FIG. 2) is being held in a rearward position and engages the angled face 589 on the arm 587 and moves the bell crank lever 579 in a direction to raise the bar 573. When the bar 573 is raised its lower front edge portion engages the recess in the rear edge of the bar 567 and prevents its endwise movement. When the bar 573 is in its lowered position a gap 593 in the bar 567 lies opposite the recess and allows the bar 573 to be moved lengthwise. When the heel support is moved forwardly by the operator the rod 591 is moved forwardly and allows the bar 573 to be moved by a spring 595, downwardly to bring the gap 593 opposite the recess in the bar 567 so that the hand lever 571 may be actuated to cause the carrier 17 to move to the left.

The aforesaid nail assorting or loading mechanism of the illustrative machine is caused to deliver six nails simultaneously to the nail driving and bending mechanism. A nail-inverting roll of the nail assorting apparatus, corresponding to the roll referred to as the nail-inverting roll 86 in the above-mentioned Patent No. 2,929,066, is actuated to deliver the nails during the first part of the complete cycle of operations of the machine and is returned to receive a new batch of nails when the carrier 17 is moved to its right-hand position. This arrangement allows adequate time for the nails to travel from the assorting mechanism to the nail driving and bending mechanism and for the nail-inverting roll to receive a new batch of nails. The nail assorting mechanism is actuated to deliver the nails by downward movement of a rod 597 (FIG. 21). The rod 597 is pivotally connected to a lever 599 which is pivoted on a stud 601 carried by the bracket 582 secured to the head 3. The lever 599 has on it an inclined face 603 which as the carrier 17 approaches its right-hand position across the machine is engaged by a roll 605 which is rotatably mounted on a stud 607 secured in the upper end portion of a bar 609 (FIG. 24) secured on the carrier 17. When the roll 605 engages the inclined face 603 the rod 597 is moved downwardly and is held in this position until the carrier 17 is moved away from its right-hand position. The upper end portion of the rod 597 is pivotally connected to a rearwardly extending arm of a bell crank lever 611 (FIG. 25) which is pivoted on a stud 613 secured in the head 3. The bell crank lever 611 has a downwardly extending arm to which is pivotally connected the rear end portion of a link 615. The front end portion of the link 615 has in it a slot 617 through which passes a pin 619 which is secured in a latch 621. The latch 621 is pivoted to the front end portion of a cam lever 623 which is pivoted on a spindle 625 secured in the head 3. The cam lever 623 is actuated by a cam secured on a shaft (not shown) corresponding to the shaft referred to as the counter shaft 75 in Patent No. 2,768,379 and in British Patent 767,967. The pin 619 is normally held against the rear end of the slot 617 by a tension spring 629 which is connected to the latch 621 and to the cam lever 623. The latch 621 is arranged

to latch over a plate 631 which is secured on arm 633 which is pivoted on the stud 613. The arm 633 has pivotally connected to it the lower end portion of a rod 635. The upper end portion of the rod 635 is pivotally connected to an arm, corresponding to the arm referred to as the arm 152 in said Patent No. 2,929,066, down-movement of which causes the nails to be delivered from the nail assorting mechanism to the nail driving and bending mechanism.

10 During rotation of the counter shaft 75 disclosed in Patent 2,768,379 while nails are being inserted into a heel and bent, the cam lever 623 first moves the latch 621 upwardly and then downwardly. During the upward movement of the latch its upper hooked end latches over the plate 631 and as the latch moves downwardly it moves the arm 633 and rod 635 downwardly and the latch holds it in this position. When, as the carrier 17 is moved to its right-hand position the rod 597 is moved downwardly and the lever 611 and link 615 move the latch 621 away from the plate 631 which allows the aforesaid nail-inverting roll to be returned by the spring referred to as 156 in said Patent No. 2,929,066.

15 After the nails N have been driven into the heel H and bent the heel support D with the heel in it is lowered to withdraw the portion of the nails, which project from the heel, from nail throats of the nail driving and bending mechanism. The heel support D is slidably mounted on the carrier 17 for up and down movement as well as forward and rearward movement and has on its under side a plate 637 (FIG. 17) which, when the heel support is in its lowered position, rests on a face 639 on the carrier 17. The heel support is moved upwardly by a plunger 641 which is slidably mounted in the forwardly extending portion of the base 1. The plunger 641 has pivotally connected to it the upper end portion of a link 643. The lower end portion of the link 643 is pivotally connected to an arm 645 of a lever 647. The link 643 and arm 645 form a toggle which is in a straightened condition when the plunger and heel support are in their raised position. The lever 647 is pivotally mounted on an eccentric portion 649 of a spindle 651 which is rotatably mounted in a bracket 653 secured in the aforesaid sump 425 in the forwardly extending portion of the base 1. The spindle 651 has on its right-hand end an arm 655 which has in it a slot 657. Slidably mounted in the slot 657 is a block 658 to which is pivotally connected the rear end portion of a rod 659. The front end portion of the rod 659 has screw threaded engagement with a sleeve rotatably mounted in the forwardly extending portion of the base 1, which sleeve has on it, at the front of the machine, a knurled collar 661 (FIG. 1). When the heel support is in its raised position and the toggle formed by the link 643 and arm 645 is therefore straightened adjustment of the rod 659 raises or lowers the heel support. The heel support may therefore be readily positioned heightwise relatively to the nail inserting and bending mechanism to bring the seat face of a heel in the heel support into proper heightwise position to receive the nails. Adjustment of the rod 659 does not affect the lower position of the heel support since the toggle will then be broken.

20 When the nails have been driven into a heel and bent the friction between the nail throats and the portions of the nails in the throats may be sufficient to prevent the heel support from moving down by gravity. To ensure that the heel support will be moved down until the plate 637 engages the face 639 on the carrier 17 the plunger 641 carries a latch member 669, which, as the plunger 641 moves downwardly, positively pulls down the heel support if it is not free to move down by gravity. The plunger 641 has secured in it a pin 671 on which is pivoted a pair of links 673, which lie in a recess in the upper end of the plunger, between which links is pivoted, on a pin 675 which is carried by the links 673, the latch member 669. The latch member 669 has at its upper end a hook or latch 677 which is arranged to latch over the plate 637.

The hook 677 is urged toward the plate 637 by a spring 679 which engages a pin 681 in the plunger 641 and an arm 683 of the latch member 669. A pin 685 in the plunger 641 limits the movement of the latch member 669 by the spring 679. The pin 675 passes through slots 687 in the plunger 641. The aforesaid lever 647 has an upwardly extending arm 689. The arm 689 is connected by a link 691 to a lever 693 pivoted on a stud 695 secured in the sump 425. The lever 693 is connected by a rod 697 to a cam lever which is operated by a cam on a cam shaft which is driven by the aforesaid belts 15 and by which the nail inserting and bending mechanism is operated.

When the illustrative machine is in its stopped position the heel support is in a forward and lowered position and when a heel has been placed in the heel support the heel support is moved rearwardly to carry the heel beneath the nail inserting and bending mechanism as described in detail in said United States Letters Patent No. 2,768,379 and in said British Patent 767,967.

When the machine is started the plunger 641 is moved upwardly and before the plunger engages the plate 637 the hook 677 snaps over the plate. The plunger 641 thereafter raises the heel support into position to receive the nails. The heel support remains in this position while the nails are driven and bent and is supported by the straightened toggle formed by the link 643 and arm of the lever 647. Just after the nails have been driven and bent the plunger 641 is moved downwardly and the heel support if it is free to do so, moves with it until the plate 637 engages the face 639 on the carrier 17.

When the plunger 641 moves downwardly the hook 677 lies above the plate 637 and after the plate 637 has engaged the face 639 on the carrier the slots 687 move down past the pin 675 but their upper ends do not engage the pin when the plunger 641 reaches its lowest position. As the carrier moves from its left-hand position toward its right-hand position the plate 637 moves away from the latch member 669 and the spring 679 moves the latch member against the pin 685 and the pin 675 against the bottom of the slots 687. As the carrier 17 is moved to its left-hand position the plate 637 moves the latch member 669 into the position shown in FIG. 17. If the heel support is prevented, as aforesaid, from moving down by gravity the hook 677 which will be over the plate 637, will be prevented from moving downwardly with the plunger 641. As the plunger 641 moves down the upper ends of the slots 687 come into engagement with the pin 675 and the heel support is positively moved downwardly. When the heel support D is free it will fall by gravity and the spring 679 will move the pin 675 away from the upper ends of the slots 687 and will hold the hook 677 against the plate 637 until the carrier 17 is moved to the right.

When the illustrative machine is in its stopped position and ready to attach a heel H to a shoe S nails N will have been delivered in the previous cycle of the machine to the nail inserting and bending mechanism B. The jack 12 will be in a raised and forward position with the post 19 swung forwardly with the last pin 39 in a convenient position to receive the last pin hole in a last having a shoe thereon. The sliding bracket 159 will be resting on the plunger 161, as shown in FIG. 4, and the various locks hereinbefore referred to will be open.

The operator places the heel H in the heel support D and moves said support rearwardly as disclosed in detail in said British Patent 767,967 causing the heel to be properly positioned and locked on the support. He then places the last L, upon which the shoe S is mounted, upon the last pin 39 and moves the shoe and post 19 rearwardly and by means of the treadle 9 brings the heel seat face of the shoe down onto the block 61 and positions it rearwardly and laterally by engaging it with the faces 95 of the arms 94 and the faces 92. As the shoe is moved down and positioned on the block 61 of the rear of its heel end portion is pressed down between the

shoe-engaging devices 239 and passes between the angled members 163.

The operator then further depresses the treadle 9 to start the machine. During the first part of the complete cycle of the machine the heel support D is raised to its operating position in the carrier 17 and nails N are inserted into the heel H and bent and a fresh supply of nails is delivered to the nail-inserting mechanism B by the nail-assorting mechanism C. Also during the first part of the complete cycle of the machine the heel support D is lowered after the nails have been partially inserted in the attaching face thereof and have had their exposed portions bent in parallel relation. Further, as soon as the heel seat of the shoe has been positioned on the block 61 the shoe clamping devices A are moved against the shoe S and are locked against movement away from the shoe and the devices are locked to the jack so that they will move upwardly with it and the jack is locked against forward movement. During the first half of the first power cycle of the machine the jack 12 is lowered under heavy pressure and the plunger 83 is raised to operate the pricking mechanism. The pricking mechanism E then pricks the heel seat of the shoe and the nail driving and bending mechanism is operated, the machine then coming to a stop. When the operator allows the treadle 9 to rise, the shoe, the shoe clamp and jack move upwardly but the locks are not opened, with the result that there is little, if any, likelihood of the lateral position of the shoe being altered. After the shoe S has been raised from the pricking block 61 and the treadle 9 moves further upwardly the carrier 17 is automatically moved to its right-hand position to carry the heel H with the nails N therein beneath the shoe. As the carrier 17 is arriving at its right-hand position the nail-inverting roll of the nail-assorting and loading mechanism C is rotated from a position in which it has delivered a supply of nails to the nail assorting mechanism to a position in which it may receive a fresh supply of nails. The operator then again depresses the treadle 9 and moves the shoe S down onto the nails N in the heel. When sufficient resistance to further downward movement of the shoe is met the further depression of the treadle again starts the machine. During the second part of the complete cycle of the machine the shoe is pressed against the heel in the heel holder, which will be in its lowered position, and the nails will be inserted in the shoe and clenched. After the heel and shoe have been attached together the locks associated with the shoe clamping and positioning devices and the locks connecting these devices to the jack are opened so that when the treadle is released the jack may move upwardly leaving the shoe supported by the heel support. The operator, when the machine has stopped, moves the heel support forwardly and removes the shoe. The operator then, by means of the hand lever 571, causes the carrier to be returned to its lefthand position. It will be appreciated that during the second part of the complete cycle of the machine the nail inserting and bending mechanism is inoperative.

Having thus described my invention, what I claim as new and desire to secure by Letters Patent of the United States is:

1. In a heel attaching machine, a plunger movable in a rectilinear path, a jack which is movably mounted on the plunger and is adapted to support a shoe, pricking mechanism and heel supporting mechanism cooperating with the jack in successive parts respectively of a split cycle of the machine to attach to the shoe a heel into the attaching face of which nails have been partly driven with projecting portions thereof arranged in parallel relation, means for locating the shoe on the jack in a predetermined operating position with relation to the plunger and the pricking mechanism, a bracket movable lengthwise of said rectilinear path, front clamps mounted for movement independently of each other on said bracket

and adapted to be moved into clamping engagement with opposite sides of the shoe in the vicinity of its heel breast line, rear clamps mounted on the bracket for movement equal distances toward and away from each other and adapted to engage the opposite sides of the rear counter portion of the shoe, means rendered active in timed relation with the plunger for operating the clamps to secure the shoe in predetermined operating positions upon the jack with relation to the plunger, mechanism for securing said clamps in their clamping positions against the shoe upon the jack until the heel has been attached to the shoe and for thereafter automatically rendering said last-named means inactive whereby to permit the shoe to be released from the jack, and manually actuated means for rendering at any stage of the operation said last-named means inactive for releasing the shoe from the jack.

2. In a heel attaching machine, a plunger movable in a predetermined path, a slide movable with said plunger and also relatively to said plunger in a path disposed at right angles to said first-named path, a post pivotally mounted on the slide, a last interengaging member carried by the post for movement therewith and slideable on said post in a path disposed at approximately right angles to each of said first- and second-named paths, a sliding bracket constrained for movement lengthwise of the path of movement of the plunger, a pricking unit, power means for moving the plunger in said first-named path toward and away from the pricking unit, gages for positioning the heel seat of a shoe, which is mounted on a last, upon the last interengaging member and upon the pricking unit in response to movement of the plunger toward said unit, a bracket movable lengthwise of said rectilinear path, front clamps mounted for movement independently of each other on said bracket and adapted to be moved into clamping engagement with opposite sides of the shoe in the vicinity of its heel breast line, rear clamps mounted on the bracket for movement equal distances toward and away from each other and adapted to engage the opposite sides of the rear counter portion of the shoe, means rendered active in timed relation with the plunger for operating the clamps to secure the shoe in predetermined operating positions upon the jack with relation to the plunger, means for securing the slide to the sliding bracket, and means for independently securing the jack post to the bracket.

3. In a heel attaching machine, a plunger movable in a rectilinear path, a slide movable with said plunger and also relatively to said plunger in a path disposed at right angles to said first-named path, a post pivotally mounted on the slide, a last engaging member journaled upon the post for movement about an axis shiftable with relation to said post in a path disposed at approximately right angles to said first- and second-named paths, a sliding bracket constrained for movement lengthwise of the path of movement of the plunger, a pricking unit, power means for moving the plunger in said first-named path toward and away from the pricking unit, gages for positioning the heel seat portion of a shoe, which is mounted on the last, upon said last-engaging member and upon the pricking unit in response to movement of the plunger toward the pricking unit, a pair of clamps mounted for independent movement on the bracket, means including a spring mounted on the bracket for constantly urging the clamps toward each other and toward opposite sides of the counter portion of the shoe positioned on the pricking unit, means which is operative in timed relation with the plunger against the action of the spring whereby to cause the clamps to be held in open positions away from the shoe, said last-named means being rendered ineffective when the shoe has been forced against the pricking unit by said power means to render the spring effective to cause the clamps to be forced against the shoe, and means for independently securing the bracket to the post and to the plunger to cause the shoe to move as a unit

with the plunger during a portion of the operation of said plunger.

4. In a heel attaching machine, a nail driving and bending unit, power means for operating said nail driving and bending unit, a shoe supporting unit, a carrier comprising a heel holder and a heel seat pricking unit, means for moving the carrier between two operating positions in the first of which the shoe supporting unit and the pricking unit are arranged opposite the nail driving and bending unit and the shoe supporting unit respectively and in the second of which positions the heel holder is arranged opposite the shoe supporting unit and the pricking unit is idle, power means operative in timed relation with said first-named power means for moving the carrier between said first and second operating positions, said holder being movable in the carrier between a loading and an unloading position and one operating position and between said one operating position and a second operating position, said holder being movable manually from the loading and unloading position to said first operating position in the carrier, power means operative in timed relation with the aforesaid power means for moving on the carrier the holder from said first operating position to said second operating position, and a latch operatively connected with said last-named power means for insuring that the holder shall be moved from said second operating position to said first operating position on the carrier before the carrier is moved from its first operating position.

5. In a heel attaching machine, a nail driving and bending unit, power means for operating said nail driving and bending unit, a shoe support, a carrier having an abutment face, a fixed main frame having one or more tracks, a heel holder and a pricking unit mounted upon the carrier, power means operative in timed relation with the first-named power means for moving the carrier along said tracks into two different operating positions in one of which the heel holder and the pricking unit are arranged respectively opposite the nail driving and bending unit and the shoe support and in the other of which positions the heel holder is arranged opposite the heel support and the pricking unit is idle, said carrier comprising a plurality of wheels movable along said tracks, a frame yieldingly mounted on the wheels for movement toward said tracks, said holder being adapted to be forced by its own weight against the abutment face of the carrier, and mechanism operated in timed relation with said aforesaid power means for moving the holder with relation to the carrier away from the abutment face of the carrier to a predetermined operating position, said frame of the carrier being yieldable upon the main frame of the machine with relation to said wheels in response to pressure imparted to the heel holder through the shoe support and work mounted therein until the frame of the carrier engages the main frame of the machine.

6. In a heel attaching machine, a nail driving and bending unit, power means for operating said nail driving and bending unit, a shoe support, a carrier having an abutment face, a fixed main frame having one or more tracks, a heel holder and a pricking unit mounted on the carrier, power means for moving the carrier along the tracks into two different operating positions in one of which the heel holder and the pricking unit are arranged respectively opposite the nail driving and bending unit and the shoe support, and in the other of which positions the heel holder is arranged opposite the shoe support and the pricking unit is idle, said carrier comprising a plurality of wheels movable on said tracks and a frame yieldingly mounted on the wheels for movement toward said tracks, said holder being adapted to be forced under its own weight against the abutment face of the carrier, mechanism operated in timed relation with said aforesaid power means for moving the holder with relation to the carrier away from the abutment face of the carrier to a predeter-

mined operating position, means for varying said operating position of the holder on the carrier in accordance with the desired operating position of the heel on said carrier with relation to the nail driving and bending unit, said frame of the carrier being yieldable upon the fixed main frame of the machine with relation to said wheels until the frame of the carrier engages said fixed frame of the machine, and a manually operated means for moving the holder on the carrier to and from a loading and unloading position on the carrier.

7. In a heel attaching machine, a nail driving and bending device, a support for a shoe, a carrier, a heel holder and a pricking unit which are mounted on the carrier, said heel holder being mounted for movement on the carrier between a loading and unloading position and an operating position, fluid pressure means which comprises a control member and is adapted to move the carrier between a first operating position in which the heel holder and the pricking unit respectively are in positions opposite the nail driving and bending unit and the shoe support and a second operating position in which the heel holder is arranged opposite the shoe support and the pricking unit is idle, means for securing the control member against movement after the carrier has been moved to its second operating position whereby to retain the carrier at its second operating position, manual means for rendering said last-named means ineffective and to cause said control member to be actuated whereby to render the fluid pressure means active to move the carrier from its second to its first operating position, and means for preventing operation of said manual means unless the heel holder is in its loading and unloading position on the carrier.

8. In a heel attaching machine, a carrier, a nail driving and bending unit, a support for a shoe, a holder mounted on the carrier, said holder being movable on the carrier between a loading and unloading position and retracted and projected operating positions in which a heel is positioned and clamped in the holder, power operated mechanism for moving the holder from said retracted operating position to said projected operating position on said carrier, means operative in timed relation with said mechanism for moving the carrier between a first operating position in which the holder is arranged opposite said nail driving and bending unit and a second operating position in which the holder is arranged opposite the shoe support, means operative in timed relation with said first named means and with said mechanism for operating said nail driving and bending unit when the carrier is in its first operating position and the holder is in its projected operating position on the carrier whereby to drive nails part way into the attaching face of the heel and to bend exposed portions of said nails into parallel relation, and a latch associated with said mechanism and adapted to insure that the holder shall be moved from its projected position to its retracted position on the carrier away from the nail driving and bending unit before the carrier is moved away from its first operating position.

9. In a heel attaching machine, a jack which comprises a post, an abutment spaced from said post, power means for moving said post in a rectilinear path toward and away from said abutment, said jack also comprising a sliding member which is yieldingly mounted on said post for movement lengthwise of said rectilinear path and is adapted to carry a shoe and which is normally shiftable on said post in a path disposed at right angles to said rectilinear path, said post and said sliding member having opposed portions, and resilient means for normally maintaining said opposed portions of the post and the sliding member spaced from each other, and gages for positioning on said abutment a heel seat of the shoe carried by the sliding member, said sliding member being adapted first to force the heel seat of the shoe yieldingly against said gages and said abutment as the post is moved

toward said abutment whereby to allow said sliding member to move in said second-named path to allow the gages to orient the heel seat of the shoe on the abutment, said sliding member being adapted as the post continues to move toward said abutment to have its opposed portion acted upon by the opposed portion of the post to cause the positioned heel seat of the shoe mounted on the sliding member to be forced positively against said abutment.

10. In a heel attaching machine, a jack which comprises a post having a presser portion, an abutment, power means for moving said post in a rectilinear path toward and away from said abutment, said jack also comprising a sliding member which is carried by the post and has a pressure receiving portion and which is adapted to carry a shoe and is yieldable with relation to said post lengthwise of said path and is normally shiftable on the post in a path disposed at right angles to said first-named path, and a spring for constantly urging the sliding member to an idle position on the post in which position the pressure receiving portion of the sliding member is spaced from the presser portion of the post, and gages for positioning the shoe mounted on the sliding member upon said abutment, said power means as it moves the post toward the abutment causing the heel seat portion of the shoe carried by the sliding member to be forced, against the action of the spring, yieldingly against the gages with the result that the sliding member shifts on said post along said second-named path as against the gages with the result that the sliding member moves with the post generally lengthwise of the first-named path, said post as it continues to move toward the abutment causing the presser portion of the post to engage the pressure receiving portion of the sliding member to force the heel seat of the shoe carried by the sliding member positively against said abutment.
11. In a heel attaching machine, a jack comprising a post having a presser portion, an abutment, power means for moving said post in a rectilinear path toward and away from said abutment, said jack comprising a sliding member which is carried by said post and has a pressure receiving portion and which is yieldable with relation to said post lengthwise of said path and is normally freely shiftable on said post in a path disposed at right angles to said first-named path, and a member which is adapted to receive a last bearing a shoe and which is pivotally mounted on said sliding member for movement about an axis disposed at right angles to said first- and second-named paths, and gages for positioning the heel seat of the shoe mounted on said member upon said abutment, said jack also comprising a spring for constantly urging the sliding member to an idle position on the post in which position the pressure receiving portion of the sliding member is spaced from the presser portion of the post, said power means as it moves the post toward the abutment causing the heel seat portion of the shoe on said member to be forced against the action of said spring yieldingly against the gages with the result that the sliding member and accordingly said member shift on the post in said second-named path as they move generally lengthwise of the first-named path and thereafter causing the presser portion of the post to engage the pressure receiving portion of the sliding member to force the heel seat of the shoe positively against said abutment.
